WILBERT BLACK, OF NEW ORLEANS, LOUISIANA.

FIRE PREVENTING AND EXTINGUISHING MEANS.

Application filed August 17, 1925. Serial No. 50,769.

My invention is a fire preventing and extinguishing means for use in tanks which hold inflammable liquids, and it consists in the combinations, constructions and arrangements herein described and claimed.

An object of the invention is the provision of simple, reliable and efficient means adapted to practically prevent combustion of inflammable liquid in a storage tank or like container, and affording facilities for extinguishing the flames should the liquid in the tank be ignited in any manner.

Other objects and advantages of the invention will be apparent from the following description considered in conjunction with the accompanying drawings, forming a part of this application, in which—

Figure 1 is a vertical section through a tank equipped with fire preventing and extinguishing means embodying the invention, showing liquid in the tank and a fire preventing and extinguishing float on the surface of the liquid.

Figure 2 is a plan view of the tank with the fire extinguishing liquid discharging conduit system shown therein, with a portion of the cover plate of the float broken away,

Figure 3 is a fragmentary vertical sectional view, showing a portion of the float and a portion of the wall of the tank,

Figure 4 is a fragmentary edge view, showing the float, and

Figure 5 is a fragmentary relatively enlarged view, partly in vertical section and partly in side elevation, showing the discharge head portion of one of the liquid conducting pipes of the fire extinguishing conduit system.

In Figures 1 and 2, the numeral 1 designates a tank which may be of any desirable configuration and size and made of any suitable relatively incombustible material. The tank 1 is provided with a lateral outlet 2 for liquid and is adapted to have liquid supplied thereto in any suitable known manner until the liquid in the tank extends to a desirable level, preferably to a level adjacent to the upper end of the tank, as indicated at L. The outlet 2 is located adjacent to the level of the bottom of the tank but it will be understood that this outlet may be provided with suitable valve means, not shown, for preventing flow of liquid from

the tank through the outlet when desired so that the liquid normally will fill the tank 55 to the level indicated at L.

The liquid in the tank may be highly inflammable and it therefore is desirable that provision be made to render ignition and combustion of the liquid in the tank difficult 60 and that provision also be made for extinguishing the flames should the liquid in the tank be ignited in any manner.

The invention contemplates the provision of a non-inflammable surface covering for 65 the liquid in the tank. This surface covering is a float which comprises a casing 3 which houses a relatively great number of small globular buoyant separate refractory members 4, made of glass, or other suitable 70 buoyant refractory or relatively incombustible material. The float casing comprising a bottom 5, a top 6—6^a, vertical radial partitions 8, and an endless body member 9 which flexibly connects the marginal edge 75 portions of the top 6—6^a and the bottom 5. The bottom 5 and the partitions 8 are made of buoyant wood while the top comprises the plate 6 made of buoyant wood and covered by the thin metallic sheet 6^a. The body 80 9 of the float casing is made of fine mesh screen wire or like material. The globular float members 4 are packed between the top 6—6^a and the bottom plate 5 of the float casing and of course between adjacent partitions 8, also. The cross sectional area of the float casing is slightly less than that of the space within the tank, so that the float can rise and fall freely with the level of liquid 85 in the tank. The body 9 of the float casing has an outwardly extending annular flange 10 which of course is of foraminous material 90 also and is in contact at its outer edge with the inner wall of the tank body. This surface covering will practically exclude the atmosphere from the liquid in the tank and therefore oxygen from the atmosphere will not be permitted to support combustion of the liquid in the tank should the latter be 95 ignited in any way.

The invention also provides a fire extinguishing liquid discharging conduit system for cooperating with the float members to extinguish the flames should the liquid in the tank be ignited and to tend to prevent fire. The liquid discharging conduit com-

prises a liquid supply pipe 11 which extends through a lateral opening 12 in the lower part of the tank to the center of the tank and is there connected with radially extending branch supply pipes 13. The supply pipe 11 has a fluid tight fit with the wall of the opening 12 in tank 1 and may lead from any suitable source of supply of liquid having fire extinguishing properties. Riser or delivery pipes 14 extend vertically through the liquid in the tank from the outer ends of the branch pipes 13 and from the main supply pipe 11. One of the riser pipes 14 is joined to the joined together portions of the main supply pipe 11 and the branch supply pipes 13 at the center of the tank and all of said riser pipes are joined at their lower ends to the pipes on which they are supported in such manner as to be in open communication with the supporting pipes. The riser pipes 14 extend above the level of liquid in the tank 1 through aligned openings in the top and bottom members of the float casing and vertical bushings, as at 15, 20, 25, 30, 35, 40, 45, 50, 55, 60, 65, 70, 75, 80, 85, 90, 95, 100, 105, 110.

The number and relative arrangement of the riser pipes are such that the entire surface of the fire protective covering on the liquid in the tank will be effectually sprayed with water or other suitable liquid which may be caused to pass upwardly through the riser pipes and to be discharged within the upper part of the tank through the perforations 19 in the discharge heads or nozzles should the inflammable liquid in the tank be ignited. The water issuing from the nozzles will serve to extinguish the flames and will cool the float and thus will cooperate with the latter to protect the inflammable liquid in the tank from fire.

Obviously, the invention is susceptible of embodiment in forms other than that illustrated in the accompanying drawings and I therefore consider as my own all such modifications and adaptations of the form of the

device herein shown as fairly fall within the scope of the appended claims.

I claim:

1. In a fire preventing means for an inflammable liquid in a tank, a float casing adapted to rise and fall with the level of liquid in the tank, and to be supported by said liquid, said float casing being made of buoyant material, a covering of light gauge relatively incombustible material on the float casing, and a plurality of globular buoyant relatively incombustible members housed within said float casing.

2. In a fire preventing means for an inflammable liquid in the tank, a float casing adapted to be supported by the liquid in the tank and to rise and fall with the level of such liquid, said float casing comprising a bottom, a top, a foraminous endless body connecting the marginal edge portions of the bottom and top of the float casing, and globular relatively incombustible members disposed between said top and bottom of said float casing.

3. In a fire preventing means for an inflammable liquid in the tank, a float casing adapted to be supported by the liquid in the tank and to rise and fall with the level of such liquid, said float casing comprising a bottom, a top, a foraminous endless body connecting the marginal edge portions of the bottom and top of the float casing, and globular relatively incombustible buoyant members disposed between said top and bottom of said float casing, and an endless flange of relatively incombustible foraminous material extending radially outward from the endless body of the float casing to the inner wall of said tank.

4. In a fire preventing means for an inflammable liquid in a tank, a float casing adapted to be supported by the liquid in the tank and to rise and fall with the level of such liquid, said float casing comprising a bottom, a top, a foraminous endless body connecting the marginal edge portions of the bottom and top of the float casing, and radially extending vertical partition walls between said bottom and the top of the float casing, globular relatively incombustible buoyant members disposed between said top and bottom of said float casing, and an endless flange of relatively incombustible foraminous material extending radially outward from the endless body of the float casing to the inner wall of said tank.

WILBERT BLACK.
